UNITED STATES PATENT OFFICE.

DAVID SHERWOOD KENNEDY, OF BROOKLYN, NEW YORK, ASSIGNOR TO MERGEN-
THALER LINOTYPE COMPANY, A CORPORATION OF NEW YORK.

TYPGRAPHICAL MACHINE.

1,081,754.

Specification of Letters Patent.

Patented Dec. 16, 1913.

Application filed April 29, 1912. Serial No. 693,934.

To all whom it may concern:

Be it known that I, DAVID SHERWOOD KENNEDY, a citizen of the United States, and a resident of Brooklyn, county of Kings, and State of New York, have invented a new and useful Improvement in Typographical Machines, of which the following is a specification.

My invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line together with expanding spacers, the composed line transferred to the face of the mold, the mold filled with molten metal to form a slug or linotype against the matrices which produce the type characters thereon, and the matrices thereafter elevated and returned through a distributing mechanism to the magazine from which they started.

More particularly, it has reference to the parts which receive the matrices from the distributing mechanism, and its general object is to adapt such parts for speedy adjustment to permit them to receive matrices of different thicknesses, as may be necessary.

My improved devices are specifically shown in connection with the kind of machine set forth in the application for Letters Patent of John R. Rogers, No. 624,426, filed May 1, 1911, wherein is employed a plurality of magazines, and means for shifting any selected one thereof into operative relation to the other parts; and wherein, further, the magazines are removably mounted, so that others may be substituted therefor at will, such interchangeable magazines corresponding to different styles and fonts of characters, and consequently containing matrices of relatively different thicknesses.

As previously indicated, only one magazine is in operation at a time, and in connection therewith is employed a single distributing mechanism, and a single intermediate channeled magazine entrance, which receives the matrices from the distributing mechanism and conveys them to the magazine. As the several magazines, which are brought successively into operative position, may contain matrices of different size and

thicknesses, it is desirable that the width of the channels of the magazine entrance may be relatively varied to correspond. These channels are ordinarily formed by partition plates corrugated at their lower extremities to act upon the sides of the matrices and guide them with accuracy. This corrugation to some extent diminishes the available space in the channels, and in order to adapt them to matrices of considerable thickness, the alteration in width has been usually accomplished by the manual shifting of certain of the partitions.

It is one purpose of my present invention to avoid the loss of time and uncertainty involved in such manipulation, and to provide means whereby the same result is secured without special attention by the operator, and which, moreover, insure the bending or shifting of the proper partitions and to the necessary extent. Preferably these means are automatically actuated, and in the form shown, by their connection to the movable shift frame which carries the magazines, in such manner that when the selected magazine is brought into position the entrance will be simultaneously adjusted to correspond thereto. Moreover I also provide devices in connection therewith, whereby the extent of variation in the width of the channels may be altered at will, this latter feature of adjustment being particularly desirable in connection with interchangeable magazines, as distinguished from those which are brought normally by the shifting frame into operative position.

In the accompanying drawings, I have shown my invention in preferred form and by way of example, and as applied to the particular kind of linotype machine described, but obviously any variations and alterations may be made therein, and further it may be applied to other forms of typographical machines, such as typesetters, typecasters, and the like, without departure from its spirit. Generally speaking, I desire it to be distinctly understood that I do not limit myself to any specific form or embodiment, except in so far as such limitations are specified in the claims.

Referring to the drawings: Figure 1 is a side view, partly in section, of a portion of the machine, illustrating particularly the shiftable magazine, etc., and having my invention applied thereto; Fig. 2 is a sectional

view, taken substantially on the line 2—2 in Fig. 1; Fig. 3 is a sectional view, taken substantially on the line 3—3 in Fig. 1; Fig. 4 is a detail, showing the mode of connection of a partition plate to the adjusting element; Fig. 5 is an enlarged sectional detail, illustrating the relation of the magazine entrance to the magazine; and Fig. 6 is a section thereof, taken substantially on the line 6—6 in Fig. 5.

The magazines A¹, A², A³ are mounted in the shift frame A, whereby any selected one thereof may be brought into operative relation to the other parts, (as indicated by dotted lines in Fig. 1), the magazine A³ being thus illustrated by way of example. The specific means for shifting the magazines and for registering and locking them in position constitute no part of my present invention. The distributing mechanism comprises the customary rail B and the screws B¹, whereby the matrices X are moved along the rail, from which they drop through the magazine entrance C into the operative magazine, as A³. The entrance C is divided into channels in the customary manner, by partitions D, which partitions are free at their lower ends, thus permitting them to be moved or bent in relation to the channels in the magazine. All of the parts so far described are old in the art, and are or may be of the form disclosed in the application previously mentioned.

As before indicated, the several magazines carry different styles or fonts, and consequently the contained matrices are of different relative thicknesses. It therefore is customary to move or bend the lower end of certain of the partitions D in order to vary relatively the width of the corresponding channels, when a new magazine comes into position. In order to effect this result mechanically I connect the lower ends of one or more of the partitions to an adjusting element. For instance, in Figs. 4, 5, and 6, a longitudinally movable strip E is shown as employed for the purpose, which strip by a notch E² therein engages the lower end of a partition D¹. In the figures mentioned, the strip E has been operated to move the partition D¹ and thus to enlarge the adjacent channel, so that it will accommodate the large or thick matrix X¹ and permit its free passage into the proper channel of the magazine A³.

The longitudinal movement of the strip E is controlled by the hook E¹ connected to the end thereof, which hook is engaged and actuated by a suitable cam piece G, or G¹. It will be noted that there is a plurality of sets of such cams G and G¹, one set for each of the magazines and located in proper relation thereto, so that as any selected magazine is brought into position, its corresponding cam will engage the hook E¹. The sev-

eral sets of cams are preferably mounted upon an arm F, rigidly connected to the shift frame A, so that the movement of the latter brings the cam into contact with the hook. The magazine entrance C, strip E, and hook E¹ are supported by the frame P, on which is also mounted a stationary guide H, which embraces the slide F and imparts additional rigidity thereto, at the time of the engagement of the operative cam thereon with the hook E¹.

The parts so far described are designed to effect the adjustment of the partitions D, and to alter the relative width of the channels in the magazine entrance C, in order to correspond to the different magazines which are successively brought into operation by the movement of the shift frame A, this result arising from the fact that the corresponding adjusting cams are carried by the shift frame and are consequently brought thereby into proper operative position simultaneously with the selected magazine. It is to be remembered, however, that the magazines A¹, A², A³, are also removably mounted in the frame A, so that others may be substituted therefor, and consequently I provide additional devices to adapt the adjusting means also to substitute magazines containing matrices of still other relative thicknesses.

Referring more particularly to Figs. 2 and 3, it will be noted that each pair of cams G and G¹ is mounted upon a spindle J, the rotation of which brings into operative position either the cam G or the cam G¹, as may be necessary in the circumstances. Each spindle J is provided with a thumb piece F¹, F², or F³, corresponding respectively to the magazines A¹, A², A³, the said thumb-piece being connected to the spindle so that the latter may be rotated thereby, the thumb-piece being capable of a slight longitudinal movement with reference thereto. Each thumb-piece is also provided with a pin L to engage in a corresponding locking notch K formed in the slide F, and a spring J¹ is interposed between the head of the spindle and the thumb-piece to hold the parts normally in their locked position. If it be desired, however, to change the cams, in the event of a magazine being removed and another one being substituted therefor, the thumb-piece may be moved outwardly against the force of the spring J¹ to free the pin L from the locking notch K, when the spindle J may be rotated to bring the selected cam into operative position, and after which the release of the thumb-piece and the action of the spring J¹ again restores the parts to their locked relation. Due to the engagement of the new cam with the hook E¹, the strip E will now be moved to a different extent, and consequently the channel partitions controlled thereby will be shifted,

and the width of the corresponding entrance channels varied, to suit the new conditions. It therefore follows that my improved devices effect the proper adjustment of the entrance channels, not only for the matrices of the magazines normally mounted in the shift frame, but in addition for the matrices of entirely different magazines that may be substituted therefor.

10 As previously pointed out, I have shown my invention in preferred form and by way of example, but obviously many variations and modifications thereof will suggest themselves to those skilled in the art and still 15 be comprised within its scope.

Having thus described my invention, its construction and mode of operation, what I claim and desire to secure by Letters Patent of the United States is as follows:

20 1. In a typographical machine, the combination of a channeled means to receive the type or matrices, with automatic means to vary the width of the channels relatively to each other to permit the passage therethrough of type or matrices of different 25 thicknesses.

2. In a typographical machine, the combination of a magazine entrance formed with a plurality of channels, with automatic 30 means to vary the width of the said channels relatively to each other to permit the passage therethrough of type or matrices of different thicknesses.

3. In a typographical machine, the combination of a magazine entrance provided with a plurality of partitions dividing it into channels, with automatic means to move certain of the partitions relatively to the others to vary the width of the corresponding channels to permit the passage therethrough of type or matrices of different thicknesses.

4. In a typographical machine, the combination of a magazine entrance provided with a plurality of partitions dividing it into channels, with automatic means to move one or more of the partitions relatively to the others to vary the relative width of the said channels, the said means comprising 50 a moving element connected to the said movable partitions.

5. In a typographical machine, the combination of a plurality of movable magazines, a channeled magazine entrance to co-operate with the magazine in operative position, and means controlled by the movement of the magazines to vary the relative width of the entrance channels.

6. In a typographical machine, the combination of a plurality of movable magazines, a magazine entrance to co-operate with the magazine in operative position, the said entrance being provided with a series of partitions dividing it into channels, and 65 means controlled by the movement of the

magazines to shift one or more of the partitions to vary the relative width of the channels.

7. In a typographical machine, the combination of a plurality of movable magazines, a magazine entrance to co-operate with the magazine in operative position, the said entrance being provided with a series of partitions dividing it into channels, and means controlled by the movement of the magazines to shift one or more of the partitions to vary the relative width of the channels, the said shifting means comprising a moving element connected to the said partitions.

8. In a typographical machine, the combination of a plurality of movable magazines, a magazine entrance to co-operate with the magazine in operative position, the said entrance being provided with a series of partitions dividing it into channels, and means controlled by the movement of the magazines to shift one or more of the partitions to vary the relative width of the channels, the said shifting means comprising an element connected to the said partitions and cams connected to the magazines to act upon and move said element.

9. In a typographical machine, the combination of a plurality of movable magazines, a channeled magazine entrance to co-operate with the magazine in operative position, and means to vary the relative width of the entrance channels, the said means comprising cams connected to the movable magazines.

10. In a typographical machine, the combination of a magazine entrance formed with a plurality of channels, with adjustable means to vary the width of the said channels relatively to each other to permit the passage therethrough of type or matrices of different thicknesses, the said means comprising manually adjustable elements to vary the extent of action of said means at will.

11. In a typographical machine, the combination of a magazine entrance provided with a plurality of partitions dividing it into channels, and a moving element connected to a plurality of said partitions whereby the widths of the channels may be simultaneously varied relatively to each other to permit the passage therethrough of type or matrices of different thicknesses.

12. In a typographical machine, a magazine entrance provided with a plurality of partitions dividing it into channels, and an element connected to one or more of said partitions, combined with automatic devices to move the said element and thus to vary relatively the width of the channels.

13. In a typographical machine, the combination of a shiftable magazine, a channeled magazine entrance to co-operate there-

4
with, and means controlled by the shifting of the magazine to vary the width of the entrance channels.

14. In a typographical machine, the combination of an interchangeable magazine, a channeled entrance to coöperate therewith, and means to vary relatively the width of the entrance channels, the said means comprising manually adjustable devices to adapt them to different magazines.

15. In a typographical machine, the combination of a plurality of shiftable magazines, the said magazines being mounted to permit their interchangeability, a channeled entrance to coöperate with the magazine in operative position, and means to vary relatively the width of the entrance channels, the said means comprising devices

to permit their adjustment to different magazines. 20

16. In a typographical machine, the combination of a channeled magazine entrance, a magazine adapted to be brought into operative relation thereto, and automatic means for varying the relative width of the entrance channels to correspond to the said magazine when brought into operative position. 25

In testimony whereof I hereunto set my hand this 26th day of April, 1912, in the presence of two attesting witnesses. 30
